APPARATUS FOR PRODUCING SEAMLESS TUBES

Filed June 20, 1921

Patented June 10, 1924.

1,497,467

UNITED STATES PATENT OFFICE.

ANDREW J. AIKEN, JR., OF CLEVELAND, OHIO.

APPARATUS FOR PRODUCING SEAMLESS TUBES.

Application filed June 20, 1921. Serial No. 476,792.

To all whom it may concern:

Be it known that I, ANDREW J. AIKEN, JR., a citizen of the United States, and a resident of Cleveland, county of Cuyahoga and State of Ohio, have invented a new and useful Improvement in Apparatus for Producing Seamless Tubes, of which the following is a specification, the principle of the invention being herein explained and the best mode in which I have contemplated applying that principle, so as to distinguish it from other inventions.

This invention relates to an apparatus for eliminating the outside seams and controlling the gauge of seamless tubes made from billets on piercing mills. More particularly, it comprises a pair of rolls or disks having a certain position adjacent the piercing mandrel, whereby they act in conjunction to knead the metal prior to its being pierced, in such a manner as to remove or break up the seams or laps produced on the outside surface, together with the use of a steady-rest for the billet as it is being reduced in size on the inlet angles of the piercing mill and a comb adjacent thereto whereby the outside surface is thoroughly combed just before the pierced billet is reduced to the wall thickness required. The expressions "comb" or "combing" refer respectively to the means and the process of cutting the longitudinal lines, or fiber, formed on a rolling mill bar when subjected to the action of the rolls in a tube mill.

Heretofore, it appears a steady-rest or comb has not been utilized in conjunction with work of this character and the seamless tubes produced have been marked by seams and lapped portions, which has detracted from the value of the product.

To avoid the disadvantages of the character noted, I associate with a pair of disks a pair of steady-rests or combs or combinations of the same, according to the size and character of the work to be operated upon and in this manner secure a product free of the defects referred to. To the accomplishment of the foregoing and related ends, said invention then, consists of the means hereinafter fully described and particularly pointed out in the claims.

The annexed drawing and the following description set forth in detail certain mechanism embodying the invention, such disclosed means constituting, however, but one

of the various mechanical forms in which the principle of the invention may be used.

In said annexed drawing:

Fig. 1 is a side elevation of the metal working parts of a piercing mill, portions thereof being shown in section;

Fig. 2 is a vertical sectional elevation taken along the line 2—2 in Fig. 1, looking in the direction of the arrows;

Fig. 3 is a partial horizontal plan view looking in the direction of the arrows 3—3 shown in Fig. 1, and showing the mechanism to either side of the apparatus illustrated in Fig. 1; and

Fig. 4 is a detail view of a modified form of the abutment adjusting device.

As illustrated in Fig. 1, adjacent a piercing mandrel, 1, of the usual construction, I position a comb roll 2 and a plain block 3, conjointly serving as a steady-rest, each of said members being adjustable toward the work and occupying positions intermediate the groove rolls hereinafter referred to. I may employ plain blocks or comb blocks and plain rolls or comb rolls, or any combination of rolls and blocks for controlling the gauge and combing the billets, that may seem desirable for the work in hand. The adjustment whereby the several elements are moved toward or away from the work is illustrated in Figs. 1 and 2. As there shown, the block 3 upon its upper side is of slightly convex shape and rests upon a base plate 4 within which it is held by means of a keyway 5 formed on its underside engaging a tapered block 6 in a recess 7 within said base plate and adjustable longitudinally of said recess by means of an adjusting screw 8 so as to be forced outwardly as its lower inclined side bears against a co-acting incline 9 at the base of said recess. A plate 11 is inset into the base block and this plate with the adjacent plate 32 hereinafter described located forwardly of the plain block referred to, serve to catch the back end of the tube as it comes over the piercing point. During the normal operation of the apparatus it is not required that the plates touch the tube, a small amount of clearance being present, as is clearly shown in Fig. 1. The adjustment of the comb roll 2 illustrated is secured by means of a pair of adjusting bolts 12, 13 engaging sockets in the upper portion of a yoke 14, the arms of which carry the journals for

100
105
110

said roll. Above each of the adjusting bolts a coil spring 15, 16, is placed, its ends bearing against the yoke and an adjustable abutment 21 through which said bolts pass. The 5 abutment has its end portions 22 tongued to fit within grooves 23 in the adjacent supporting blocks 25 and its central portion is provided with an upstanding stud 26, screw threaded for its entire distance and engaged 10 within an internally threaded collar 27 fitted within the top plate 28 of the support and secured thereto by means of a detachable flange 29 held thereto by suitable fastenings shown as a pair of set screws, 31. 15 In Fig. 4 there is shown a modified form of adjusting device for the abutment, the top plate 38 being formed with a transverse recess adjacent the stud 26, within which is housed an adjusting nut 30, the rotation of 20 which changes the position of the abutment 21. The under side of the top plate has formed integrally therewith a pair of blocks 25, which carry the guiding grooves heretofore referred to and at their lower sides 25 carry a pair of plates 32 of hardened metal, said plates being provided with screw threaded recesses 33, whereby they are secured in position, and held against the adjacent blocks by means of bolts 34, the lower 30 ends of which engage said screw threaded recesses in the plates.

As illustrated in Fig. 3, upon each side of the piercing mandrel 1, there are provided upon the frame of the mill a pair of opposed reducing and feeding disks 41, 42, which are preferably mounted upon parallel axes and in staggered relation to each other. Thus, as clearly shown in said figure, the effective portions of the rim of one disk 35 overlaps the effective portion of the opposite disk and together they form a pass above the piercing mandrel, narrowing from the inlet portion to a point just beyond the extreme end of the piercing mandrel and 40 thence widening to a size corresponding to the permanent faces of the work. The axes of such disks may be oppositely positioned but inclined toward one another or they may be parallel to one another and in spaced 45 relation so that the peripheries of the respective disks overlap, as shown in the preferred form of the construction in Fig. 3.

Through the construction above illustrated, the floating of the billet at the nose 55 of the piercing point is avoided and the piercing point will thus serve to provide a product of uniform gauge and will not travel to the hottest side of the billet. The pierced tube does not thrust against the outlet guides as in the present practice and guide scratches are avoided. The piercing bar is held steady and the tubes can be pierced with a thin wall, without buckling. 60 This construction prolongs the life of the piercing point as the flow of metal is not

retarded by thrusting against the guides, as in the practice now commonly used. The billet, it will be noted, is combed, rolled and recombed as it advances, allowing the piercing mill disks or rolls to get below the outer 70 seams in the billet and work upon solid metal. The depth of combing should be sufficient to penetrate and thus eliminate such seams as are now removed from tubes by finishing operations, such as filing or 75 grinding, after the forming of the tubes is completed. The pitch of the comb must be carefully adjusted so as to permit the comb to operate upon the metal without retarding it as it advances in the piercing mill. 80

Other modes of applying the principle of my invention may be employed instead of the one explained, change being made as regards mechanism herein disclosed, provided the means stated by any of the following claims or the equivalent of such stated means be employed. 85

I therefore particularly point out and distinctly claim as my invention:—

1. In a piercing mill, a piercing point, 90 and means contacting with the work along a narrow area immediately adjacent to and transversely in alignment with said piercing point for controlling the gauge of the tube.

2. In a piercing mill, a piercing point, a 95 pair of feeding elements adjacent said point and an intermediate element for controlling the gauge of the tube and contacting continuously with the work immediately adjacent to and transversely in line with the 100 nose of said piercing point.

3. In a piercing mill, a piercing point, a pair of feeding elements adjacent said point and a pair of intermediate elements for controlling the gauge of the tube and contacting continuously with the work immediately adjacent to and transversely in line with the 105 nose of said piercing point.

4. In a piercing mill, a piercing point, a pair of feeding elements adjacent said point and a pair of intermediate elements for controlling the gauge of the tube and contacting continuously with the work immediately adjacent to and transversely in line with the 110 nose of said piercing point, one of said elements comprising a combing member and its co-acting element being a plain guide-block. 115

5. In a piercing mill, a piercing point, a 120 pair of feeding elements adjacent said point and a pair of intermediate elements for controlling the gauge of the tube and contacting continuously with the work immediately adjacent to and transversely in line with the 125 nose of said piercing point, one of said elements comprising a combing roll and its co-acting element being a plain guide block.

6. In a piercing mill, a piercing point, a pair of feeding elements adjacent said point, a pair of intermediate elements for control- 130

ling the gauge of the tube and contacting continuously with the work immediately adjacent to and transversely in line with the nose of said piercing point, one of said elements comprising a combing roll and its co-acting element being a plain guide block, and means for adjusting each of said elements.

7. In a piercing mill, a piercing point and 10 a pair of adjustable steadyng elements in

line with said piercing point and contacting substantially continuously with the metal at the point where the metal is reducing in size.

8. In a piercing mill, a piercing point, and a pair of adjustable steadyng elements 15 immediately adjacent to and transversely in line with said piercing point, one of said elements comprising a combing roll.

Signed by me this 30th day of April, 1921.
ANDREW J. AIKEN, JR.
